UNITED STATES PATENT OFFICE.

HERBERT G. SCHMITZ, OF CHICAGO, ILLINOIS.

DOOR LATCH.

Application filed January 5, 1917, Serial No. 140,683. Renewed February 7, 1923.

To all whom it may concern:

Be it known that I, HERBERT G. SCHMITZ, a citizen of the United States, residing at Chicago, in the county of Cook and State 5 of Illinois, have invented certain new and useful Improvements in Door Latches, of which the following is a specification.

My invention relates to improvements in door locks or catches, and is particularly 10 suitable for use in connection with vehicles, for instance, automobiles.

The object of the invention is to provide a simple, inexpensive, practical, and efficient lock or catch construction so organized that 15 it may be readily applied to ordinary doors, may be easily manipulated, both in opening and in closing the door, a construction such that the effects of wear will not impair its efficiency or cause rattle or shake, either of 20 the catch or of the door itself, and, in general, to provide an improved door catch or lock of the character referred to.

In the drawings, which illustrate one application of my invention as applied to the 25 door and body of an automobile,—

Fig. 1 is a broken-out elevation of a portion of the automobile body and the door, looking from the interior of the car;

Fig. 2 is an enlarged view of a portion 30 of Fig. 1, showing the catch retracted;

Fig. 3 is a section looking along the line 3—3 of Fig. 2;

Fig. 4 is a broken-out elevation of a modified form of lock or catch, showing the parts 35 in locked position;

Fig. 5 is a view similar to Fig. 4, but showing the parts in disengaged position; and

Fig. 6 is an enlarged fragmentary view of 40 a portion of Fig. 4.

In the drawings, 10 represents the body or casing part of an automobile, and 11 is the usual door mounted to swing upon the hinges 12 and 13. In the casing 10 of the 45 body I provide an L-shaped slot or aperture 14 of sufficient lateral width to slidably accommodate a bolt or lock bar 15 mounted in the door 11.

The lock bar 15 slides in a long aperture 50 or slot 16 formed in the door 11, the open end of said aperture 16 registering with the open end of the slot 14 when the door is closed. In the inner end of the opening 16 I insert a compression coil spring 17 which 55 engages a washer or plate 18 at the end of

the lock bar 15, and this tends to force the lock bar 15 outwardly and into the L-shaped slot 14. In the door and beneath the aperture 16 is a pair of axially vertical cylindrical bores into which are fitted a pair of 60 cylindrical open-ended thimbles 19 containing plungers 20 and coil compression springs 21, the plungers 20 each having a reduced stem 22 guided by and passing through the bottom closed end of each of the thimbles 19. 65

Above the lock bar 15 and in the door there is formed an aperture or opening 23 containing an operating lever 24 pivoted upon a horizontal shaft or pin 25 secured in the door. Upon the lower end of said lever 70 24 I mount a pivoted roller 26 which is arranged to engage and depress the lock bar 15, overcoming the springs 21 whenever the lever 24 is oscillated.

When the lever 24 is in the position shown 75 in Fig. 1, the spring 17 is free to push the slide bar 15 into the aperture 14 in the door casing, and the springs 19 at the same time force the lock bar upwardly so that the upwardly projecting end 27 of the lock bar 80 engages in the upper pocket 28 of the L-shaped slot 14, thereby locking the door and at the same time preventing the lock bar and door from moving or rattling. When in locked position, the projection 29 on the inner end of the lock bar 15 engages in the notch 30 and effectually prevents any rattling or other movement of the lock bar. 85

Referring to Fig. 3, it will be seen that the upper end of the operating lever 24 90 has an inward crank or offset which projects through the facing plate or escutcheon 31 screwed or otherwise secured to the inner face of the door 11, said escutcheon 31 having an arcuate slot 32 to permit oscillatory movements of the lever 24. The inner end of the offset portion is furnished with a ball 33, or other suitable finger piece, for operating lever 24, and between the escutcheon 31 and the said ball piece 33 the crank has 100 a small tit or projection 34 which registers with a small notch or opening 35 in the escutcheon 31 when the operating lever 24 is in the position shown in Figs. 2 and 3, i. e., in unlocked position. 105

To unlock the door, the lever 24 is moved from the position shown in Fig. 1 to the position shown in Fig. 2. During the first portion of said movement, the roller 26 will engage and depress the lock bar 15, there- 110

by withdrawing the projection 27 from the pocket 28, after which the roller 26 will engage an upstanding lug or projection 36 on the upper side of the lock bar which will result in the latter being moved rearwardly against the influence of the spring 17. When the lever 24 has been moved into the position shown in Fig. 2, the lock bar 15 has been withdrawn completely from the L-shaped slot 14 in the casing and occupies the position shown in Fig. 2, in which position the door can be readily swung open on its hinges. Also, when the lever is in such unlocked position, the tit 34 enters the small notch 35 in the escutcheon 31 and holds the lock bar 15 in retracted position so that the door may be readily closed when occasion requires. The tit 34 may be held in engagement with the locking notch 35, either by the inherent resiliency of the lever 24 or by pressing the finger ball 33, a slight clearance or looseness being provided, if desired, in the pivotal mounting of the lever 24 so as to permit a slight axial movement of the lever.

The above construction is self-locking, for the reason that when the door is slammed shut, the tit or projection 34 is, by the inertia of the moving parts, shaken or moved out of engagement with the locking notch 35 in the escutcheon, the spring 17 thereupon moves the locking bar 15 outwardly into position, and the springs 21 force it upwardly into locked position.

In Figs. 4 and 5 I have illustrated another application of my invention which in some respects is superior to the one previously described. In this modification, I employ a diamond-shaped catch or locking dog 37 which is pivotally mounted in the upper pocket 38 of the casing slot upon a transverse pin 39. With this construction, the offset 40 at the end of the locking bar is undercut, as shown at 41, in order to properly cooperate with the diamond-shaped dog 37. It will be understood that in order to permit the depression of the lock bar by means of the lever 24', it will be necessary to scoop out or scallop the inner face of the diamond-shaped dog, as shown at 42. The arrangement and dimensions of the parts just described are such that when the lock bar 15' is in locked position, the lower point 43 of the diamond-shaped dog 37 engages in the corner 44 at the end of the lock bar 15'. In such position also the oblique lug 29' on the upper side of the lock bar 15' engages in the oblique notch 30' and in conjunction with the said springs and the diamond-shaped dog 37, effectually locks the parts in fixed position, even though the door has been in use for a long time and the various rubbing surfaces have been subjected to considerable wear.

Fig. 5 shows the position of the parts

in the modified arrangement when the locking bar 15' has been withdrawn prior to the opening of the door. Referring to said figure, it will be seen that the diamond-shaped dog 37 has been rotated by the point of the lock bar and occupies the position shown, with its point 43 resting against the lower edge of the pocket 38. It is understood that the dog 37 is maintained by gravity in said position, its upper end being considerably heavier than the point 43, so that when the locking bar 15' is withdrawn, there will be no tendency for the dog 37 to swing into locked position and so prevent the insertion of the locking bar.

It will be understood that the details of construction are capable of considerable modification without sacrifice of efficiency; hence, the scope of my invention must be determined by referring to the appended claims.

I claim:

1. The combination of a door casing and door provided with an L-shaped aperture and a longitudinally movable bolt having an L-shaped end adapted to enter said aperture and interlock therewith upon the transverse movement of said bolt subsequent to its entering said aperture for fastening the door in closed position in the casing, spring means for automatically pressing said bolt longitudinally into said aperture and transversely moving said bolt whereby interlocking engagement of said L-shaped part with said L-shaped aperture is effected, a manually operable lever mounted adjacent said bolt for effecting transverse and longitudinal movements of said bolt, and a pivoted dog mounted on said casing and co-operating with the end of said bolt.

2. The combination with a door and its casing, of a bolt longitudinally movable to fasten the door in closed position in the casing, a spring for pressing the bolt longitudinally, resilient means for pressing the bolt transversely to hold it in locked position, and a manually operating lever extending laterally from the bolt in the direction of its transverse movement and operable to first press the bolt transversely against said resilient means and then move it longitudinally against the spring.

3. The combination with a door and its casing, each having latching notches, of a longitudinally movable bolt having projections to engage the notches by a lateral movement of the bolt, a spring for pressing the bolt longitudinally, resilient means for pressing the bolt transversely to hold it in the locking notches, and a manually-operated lever for first pressing the bolt laterally to disengage the projections thereof from the notches and then moving it longitudinally against the spring.

4. The combination with a door and its

casing, of a bolt movable longitudinally to interlock the door and casing, separate means for pressing the bolt longitudinally and transversely to hold it in locking position, a slotted guide-plate having a notch at one end and a manually operating lever for engaging the bolt to move it first transversely and then longitudinally in the unlocking direction, and having a projection engageable in the notch in the guide-plate for holding the bolt in the unlocked position.

5. A door latch comprising a longitudinally and transversely movable bolt, resilient means for pressing it into locking position, a fixed pivoting pin, a guide-plate with a notch at one end and an operating lever mounted on the pivoting pin for controlling the movement of the bolt in both directions and having one end which extends through the guide-plate with a projection for engaging the notch thereof, the lever being axially movable on the pivoting pin to disengage the projection thereof from the notch of the locking plate.

6. The combination with a door and its casing of a bolt movable to fasten the door in the closed position in the casing, a spring for moving the bolt longitudinally to the fastening position, an operating lever for retracting the bolt against the tension of the spring, said operating lever being provided with a latch for holding the lever in position to maintain the bolt in the retracted position, said latch being automatically released by closing the door and manually released by manipulating the lever.

7. The combination with a door and its casing of a longitudinally movable bolt, a socket adapted to receive the end of the bolt for fastening the door in the closed position in the casing, means to impart a lateral movement to the end of the bolt when inserted in the socket and a pivoted member operated by the lateral movement of the end of the bolt to apply pressure to said end of the bolt to hold the bolt at a tension in the fastening position.

HERBERT G. SCHMITZ.
